UNITED STATES PATENT OFFICE.

HENRY A. STEINKAMP, OF ST. LOUIS, MISSOURI.

AUDIBLE-SIGNAL DEVICE FOR LATHES.

No. 896,419.

Specification of Letters Patent.

Patented Aug. 18, 1908.

Application filed July 15, 1907. Serial No. 383,742.

To all whom it may concern:

Be it known that I, HENRY A. STEINKAMP, a citizen of the United States of America, residing at the city of St. Louis, in the State of Missouri, have invented certain new and useful Improvements in Audible-Signal Devices for Lathes, of which the following is a full, clear, and exact description, reference being had to the accompanying drawings, forming 5 part of this specification.

My invention relates to a new and useful improvement in audible signal devices for lathes and is designed more particularly for use in screw thread cutting, whereby after 15 the ordinary screw thread cutting tool of the lathe has made its first cut, an audible signal will tell the operator just when the cutting tool is to be inserted into the work in proper time to catch the thread previously partly 20 cut.

Figure I is a front elevation of my signal device together with a portion of a lathe feed screw coöperable therewith. Fig. II is a vertical section taken on the line II—II 25 Fig. I. Fig. III is a detail section taken on the line III—III Fig. II. Fig. IV is a detail section taken on the line IV—IV Fig. II. Fig. V is a plan view of the device, on a larger scale, its cover plate being omitted, 30 parts being shown in section, and including a portion of a lathe feed screw and a portion of a supporting means for the device. Figs. VI to XI are detail vertical sections showing different positions of the vertical slides, and 35 the radial tumblers of the device.

A represents a portion of a lathe feed screw, B my signal device in its entirety, and C (Fig. V) the supporting means for the device which latter holds the device in or out of 40 coöperating relation with said feed screw.

1 designates a vertical shaft which has fixed thereto, preferably at its lowermost end, a pinion or spur gear 2 which is coöperable with the horizontal lathe feed screw A in the 45 nature of a worm gear. I prefer to form this pinion 2 with teeth cut parallel with the vertical shaft 1, rather than at an angle complementary to the lathe feed screw, in order that the pinion will mesh with either a right 50 or left hand screw thread. The vertical shaft is provided with a longitudinally disposed key seat 1^a.

3 designates a horizontally mounted cup shaped body, preferably in the form of a metallic casting, having a bottom sleeve 4

through which the vertical shaft 1 passes. This body is also provided with a laterally projecting horizontally perforated lug 5 which is designed to receive a horizontal bar c conjoined to the supporting means C, Fig. 60 V, the body 3 being adjustably secured to said bar c by means of a set screw 6.

7 designates a tumbler carrying member which is fixed to the vertical shaft so as to be rotatable with and non-rotatable, but longitudinally slideable on, the vertical shaft 1 and is designed to be located within the cup shaped body 3. The non-rotatable but longitudinal slideable feature of this tumbler carrying member 7 is produced by means of a pin 8 Fig. V, which passes through said member and enters the key seat 1^a of the shaft 1. This tumbler carrying member 7 consists of a cylindrical body portion, which surrounds the vertical shaft 1, and has a plurality of 75 radially disposed slotted or bifurcated arms 9, in this instance four, and, pivotally supported by each of these arms 9, and located within their slots are radial tumblers 10, 10^a, 10^b, and 10^c. These tumblers are free to 80 swing upwardly on their pivots. A more detailed description of these radial tumblers and the function they perform will herein-after be described.

11 designates a cover plate for the cup shaped body 3, which cover plate is practically a disk, which fits within a counter bore formed in the body 3, and is provided with a boss 11^a having a bore which receives the vertical shaft 1. 90

12 designates a collar which is secured to the vertical shaft 1, by means of a set screw, and is designed to rest upon the boss 11^a of the cover plate 11 whereby the latter is held to its seat upon the body 3. 95

13 designates a lateral flange or ledge which projects from the cup shaped body 3, and upon this ledge is supported a post 14 to which is pivotally secured a spring actuated bell hammer 15. 100

16 designates another lateral flange or ledge, which projects from the cup shaped body 3, and which supports a post 16^a, carrying a bell 17, said bell being located in juxtaposition to the free end of the bell hammer 15. 105

18 designates a three-armed rockable trip which is also mounted by a post 18^c upon the ledge 13 and is so located that one arm 18^a thereof extends through a slot 19 in the wall of the body 3, into the path of travel of the 110

radial tumblers 10, 10^a, 10^b, 10^c, while its other arm or arms 18^b coöperate with the bell hammer 15.

20 and 21 designate a pair of vertically mounted slide bars which operate in a suitable guide 22, preferably formed integral with and depending from the lower side of the body 3. These slide bars are designed to be raised or lowered either individually or collectively into or out of the path of travel of the radial tumblers 10, 10^a, 10^b, and 10^c, as desired, and are limited in their movement by means of a notch and pin connection, as is clearly illustrated in Fig. IV of the drawings, and are also securely held in their desired position by means of a set screw 23.

The audible signal, to be produced by this invention, is to be effected at every complete rotation, every one half revolution, or every one fourth revolution of the vertical shaft 1 and its carried elements which rotate therewith, depending upon the length of thread the lathe is to cut, and in order that the operator may know just when to insert the screw thread cutting tool into the thread previously cut upon the work, or in other words so that the cutting tool will enter exactly and follow upon its next cut the thread previously partly cut. For example if the lathe feed screw has a pitch of four threads to the inch and it is desired to cut a thread on a piece of work three and one half (3½") inches long the slide bars 21 and 22 are both brought to a position so that an audible signal will be produced only upon one complete revolution of the vertical shaft 1, for the reason that the pinion 2 on said vertical shaft has sixteen teeth and that, starting from a given point, which should be just after the bell has sounded, the lathe feed screw will cause the cutting tool which is cutting the thread upon the work to travel a distance of three and one half inches which means that the vertical shaft 1 will have made seven eighths of a revolution. The tool is now withdrawn from the work and brought back to a starting position which can be easily accomplished in the one eighth revolution of the vertical shaft 1 yet to follow before the bell will be again sounded, and, upon the striking of the bell the operator immediately inserts the cutting tool into the work and has caught the thread exactly, with no appreciable skill on his part. If only one and a half inches of thread, or there about, is to be cut upon the work the device will be set so that the bell will ring at every half of a revolution of the vertical shaft, or if a thread less than an inch in length is to be cut the device is so set that the bell will ring at every fourth of a revolution of the shaft.

The radial tumblers 10, and 10^a, are of different shapes, and the radial tumblers 10^b and 10^c are of the same shape the two former 10, 10^a, being arranged diametrically oppo-

site each other in the tumbler carrying member 7, and each provided respectively with a narrow notch 10^d and a wide notch 10^e formed in its lowermost face, the former narrow notch 10^d of which is in width equal to the thickness of and in alinement with the outer slide bar 20 only while the latter wide notch 10^e is in width equal to the combined thickness of and in alinement with both the outer slide bar 20 and its companion inner slide bar 21. The radial tumblers 10^b and 10^c, which are also arranged diametrically opposite each other in the tumbler carrying member 7, have no notched under face and are identical in construction. When both of the slide bars 20 and 21 are in their lowermost position as shown in Figs. II, IV, VI and VII all of the radial tumblers will remain in a lowered position, i. e. resting upon the upper face of the bottom wall of the cup shaped body 3, and be each free to engage in their rotation, the arm 18^a of the rockable post 18 thus causing, in one complete rotation of the vertical shaft 1, four taps of the bell 17.

When two taps of the bell 17 are to be produced to each revolution of the main vertical shaft 1, the outer slide bar 20 is raised to its uppermost position, as shown in Figs. VIII and IX of the drawings, whereupon it will be observed that each of the radial tumblers 10^b and 10^c will, in their passage over the outer slide bar 20, be elevated a sufficient distance to pass over the arm 18^a of the trip 18, while the two remaining radial tumblers 10 and 10^a, will not be elevated, due to their narrow and wide notches 10^d and 10^e respectively permitting them to pass the outer slide bar 20, and contact with the arm 18^a thus making the two taps of the bell to each revolution of the vertical shaft 1.

When only one tap of the bell to each revolution of the vertical shaft 1 is desired the inner slide bar 21 is raised to its uppermost position, the outer slide bar 20 either remaining in its elevated position or not, whereupon it will be observed from an inspection of Figs. X and XI of the drawings, that the radial tumblers 10, 10^b and 10^c will, in their passage over the inner slide bar 21 be elevated a sufficient distance to pass over the arm 18^a of the trip 18 and produce no movement of the latter, while the remaining radial tumbler 10^a will retain its lowermost position, by virtue of its wide notch 10^e permitting it to pass freely by the slide bar 21 and causing it to contact with the arm 18^a of the trip 18 and ring the bell.

I claim:

1. In a device of the character described the combination with a support, of a rotatable element mounted upon said support, a tumbler carrying element mounted upon said rotatable element, a plurality of tumblers carried by said tumbler carrying element, an audible signal element, a hammer

105

110

130

for said audible signal element, means coöperable with said tumblers and said hammer for producing an audible signal and a slide bar for causing one of said tumblers to be carried 5 out of a course in which it is operative upon said signal means, substantially as described.

2. In a device of the character described the combination with a support, of a rotatable element mounted upon said support, a 10 tumbler carrying element mounted upon said rotatable element, a plurality of tumblers carried by said tumbler carrying element, an audible signal element, a hammer for said audible signal element, means coöperable 15 with said tumblers and said hammer for producing an audible signal, one of said tumblers being provided with a notch, an audible signal element, means coöperable with said tumbler and said hammer for producing 20 an audible signal, a slide bar which is so located that in one position it will permit the tumbler having the notch to pass uninterrupted by it but will carry one tumbler out of a course in which it is operative upon 25 said signal means, substantially as described.

3. A device of the character described, comprising a supporting means, a shaft, a sig-

nal, means for operating the signal, a tumbler carrying member fixed to the shaft, radial tumblers carried by the tumbler carrying member and adapted to engage the signal operating means, and an adjustable slide bar for elevating one of the tumblers to a position above the signal operating means so as to enable it to pass over the latter. 30

4. A device of the character described, comprising a supporting means, a shaft, a signal, means for operating the signal, a tumbler carrying member fixed to the shaft, plain radial tumblers carried by the tumbler 40 carrying member, arranged diametrically opposite each other and adapted to engage the signal operating means, radial tumblers having narrow and wide notches respectively, arranged diametrically opposite each other 45 between the plain radial tumblers, and adapted to engage the signal operating means, and outer and inner adjustable slide bars for elevating the plain and the narrow notched tumblers.

HENRY A. STEINKAMP.

In presence of—

J. W. WESTON,
HARRY R. GATES.
